V. ROSS ET AL

WINDOW FRONT CONSTRUCTION

Filed March 6, 1922

UNITED STATES PATENT OFFICE.

VERNON ROSS AND ERRETT S. RHOADS, OF KANSAS CITY, MISSOURI, ASSIGNEES TO ROSS RHOADS COMPANY, OF KANSAS CITY, MISSOURI, A CORPORATION OF MISSOURI.

WINDOW-FRONT CONSTRUCTION.

Application filed March 6, 1922. Serial No. 541,406.

To all whom it may concern:

Be it known that we, **VERNON** Ross and **ERRETT S. RHOADS**, citizens of the United States, and residents of Kansas City, Jackson County, State of Missouri, have invented a certain new and useful Improvement in Window-Front Construction, of which the following is a complete specification.

This invention relates to store front construction and more especially to plate glass window settings and is an improvement over our copending application for store front construction, filed July 12, 1921, Serial No. 500,204, and the object of this invention is to provide a less expensive setting, one which can be put in by relatively unskilled labor, and which is more efficient than the device of the invention above set forth.

With the objects named in view, the invention consists in certain novel and useful features of construction and organization of parts, as hereinafter described and claimed; and in order that it may be fully understood, reference is to be had to the accompanying drawing, in which:—

Figure 1 illustrates a broken face view of the window setting in operative relation to a window light;

Figure 2 is a top plan view of the same with the window light in section;

Figure 3 is a sectional perspective view of the sill portion of a window light setting;

Figure 4 is a horizontal section of a side portion of the setting; and

Figure 5 is a perspective view of a clamp-chair forming a part of the setting.

In the said drawing, where like reference characters identify corresponding parts in all of the figures, 1 illustrates the sill or bottom portion of the framing and 2 the framing at the sides and top of the window light.

The framing is of substantially right-angle shape and the sill portion thereof is covered by an angular sheathing plate 3, the upper end of the vertical portion thereof being bent inwardly over the upper edge of the sill and formed with a gutter bead 4 to prevent the overflow of water condensed on the inner face of the window light. In order to provide means for the escape of such water, a series of ribs 5, are impressed on the vertical face of the sheathing and

against which the window light G is adapted to press. In this connection, it is 55 desirable to point out that it will be unnecessary to provide a sheathing at the top and sides of the window light as all water of condensation will collect at the bottom of the window.

Spaced at suitable distances around the window light, in the case of the sill, abutting the sheathing and on the sides and top abutting directly against the framing, and adapted to prevent edgewise and outward movement of the window light, are a series of clamps 6 bent to substantially triangular form. At its rear edge each chair is formed with a vertical portion 7 forming an abutment portion and having a suitable opening 8 for the passage of a screw, hereinafter referred to, and the upper end of said portion 7 is bent outwardly to form a ledge 9 against which the edge of the window light is adapted to abut and be held thereby against edgewise movement.

The base portion 10 of the member 6 rests on the horizontal portion of the sheathing, and at the sides and top of the window light (see Figure 4), is directly in contact 80 with the framing. Stamped out of portion 10 is a tongue 11, provided at its extremity with a lip 12 forming a recess 13 for the reception of the edge of the molding strip, as will hereinafter appear.

Substantially in the center of the portion of the clamp-chair 6 corresponding to the hypotenuse of a triangle, is formed an opening 14, and centrally of the upper edge of said chair portion is formed a lip 15, 90 slightly dished in order to add to its stiffness, and at opposite sides of said lip the upper end of said portion of the chair is inturned as at 16 in order to provide a pair of lugs adapted to press against the window 95 light and hold the same against outward movement.

The clamp-chairs are spaced along the edge of the window light as found desirable and at suitable points holes are punched in the vertical portion of the sheathing 3 in order to provide for the passage of screw 17, passing through the openings 14 and the openings 8. The head of the screw will come into contact with the sloping face of 105 the chair, and will engage the framing at

its other end; upon continued turning of the screw, it will be evident that the sloping face of the chair will be pulled inwardly until its lugs 16 clamp against the face of the window light, and reliably hold the same against movement. In this connection it will be evident that a chair may be placed at any point along the sill that proves advisable, uniform spacing being unnecessary as will be readily understood. As the chair is made of resilient material, it will be apparent that it will accommodate glass of any desired thickness, and that the pressure of the lugs on the face of the window light may be regulated as found desirable by means of the screw 17, it being understood, however, that the inclined portion of the chair although capable of hinge or pivoted movement at its junction with portion 10, applies through the action of the screw 17, unyielding pressure on the edge of the window light.

A molding strip 18, provided at one edge with a hook portion 19, and at its other edge with a hook portion 20, and of resilient material, is adapted to cover the chairs to prevent the entry of dirt and also to hide and conceal the operative parts of the setting. The hook portion 20 is adapted to be snapped under the lip 12 and into the recess 13, and the end 19 is snapped over the lip 15 and fits between the same and the window light. It is desirable, in this connection, to state that the parts just-described, are so proportioned that the hook 19 will be slightly spaced from the face of the window light regardless of the thickness thereof and of the angle of the inclined portion of the chair, the lugs 16 of the chair being depended upon to retain such light against outward movement.

At suitable points along the length of the molding, openings 21 are formed for the escape of any water which may collect within the window setting as will be readily understood by one skilled in the art, said openings also providing for such circulation of air as will tend to prevent the frosting of the window light.

It is desirable that the sheathing shall be sufficiently thin and of such character that the fastening screws may be forced through it as desired without the provision of specially made holes, so that it is unnecessary to place the chairs at exactly predetermined points along the framing, the weight and size of the window light determining the number and spacing of the chairs used in any part of the setting.

From the above description it will be apparent that we have produced a device of the character described, which possesses all of the features of advantage set forth as desirable, and while we have described and claimed the preferred embodiment of the

same, we reserve the right to make all changes properly falling within the spirit and scope of the appended claims.

We claim:

1. A window structure comprising a framing enclosing the window light, a clamp of substantially triangular form associated with the framing, one end of said clamp forming an abutment portion to prevent inward sliding movement of the clamp and the other end of said clamp terminating in a lug, and means for applying unyielding pressure on the portion of the clamp carrying the lug to cause said lug to contact directly with the glass and hold the same against outward movement. 70

2. A window structure comprising a framing enclosing the window light, a clamp of substantially triangular form associated with the framing, one end of said clamp forming an abutment to prevent inward sliding movement of the clamp, the other end of said clamp terminating in a lug, and a portion of said clamp intermediate said ends forming a tongue, means for applying unyielding pressure on the portion of the clamp carrying the lug to cause said lug to clamp the glass against outward movement, and a molding covering the clamp and detachably interlocked at one edge with said tongue and at its other edge with the lug-equipped end of the clamp. 85

3. A window structure comprising a framing enclosing the window light, a clamp of substantially triangular form engaging the framing, one end of said clamp forming an abutment portion to prevent inwardly sliding movement of the clamp, the other end of said clamp terminating in a lug and a lip, and a portion of said clamp intermediate said ends forming a tongue, means for applying unyielding pressure on the portion of said clamp carrying the lug to cause said lug to clamp the glass against outward movement, and a molding covering the clamp and detachably interlocked at its edges with said lip and tongue, respectively. 100

4. A window structure comprising a framing enclosing the window light, a clamp of substantially triangular form engaging the framing, one end of said clamp forming an abutment to prevent inward sliding movement of the clamp and the other end of said clamp terminating in a lug, and means for applying unyielding pressure on the portion of the clamp carrying the lug to cause said lug to contact directly with the glass and hold the same against outward movement, said means adjustably engaging the framing. 110

5. A window structure comprising a framing enclosing the window light, a sheathing of substantially the same form as said framing and resting thereon, a clamp of substantially triangular form engaging said sheath- 120

ing, one end of said clamp forming an abutment to prevent inwardly sliding movement of the clamp and the other end of said clamp terminating in a lug, and means for applying unyielding pressure on the portion of said clamp carrying the lug to cause said lug to clamp the glass between the sheathing and lug.

6. A window structure comprising a framing enclosing the window light, a clamp of substantially triangular form engaging the framing, one end of said clamp forming a ledge against which the edge of the glass will abut, the other end of the clamp ter-

minating in a lug and a lip, and a portion of said clamp intermediate its ends forming a tongue, means for applying unyielding pressure on the portion of said clamp carrying the lug to cause said lug to clamp the glass against outward movement, and a molding covering the clamp and detachably interlocked at its edges with said lip and tongue, respectively.

In witness whereof we hereunto affix our signatures.

VERNON ROSS.
ERRETT S. RHOADS.
